UNITED STATES PATENT OFFICE.

WILLIAM JEWETT, OF RICHMOND, VIRGINIA.

HAND-OPERATED BLOWER.

Application filed October 22, 1921. Serial No. 509,511.

To all whom it may concern:

Be it known that I, WILLIAM JEWETT, a citizen of the United States, residing at Richmond, in the county of Henrico and State of Virginia, have invented new and useful Improvements in Hand-Operated Blowers, of which the following is a specification.

In the ordinary construction of blast blowers, air is admitted to the blast fan through a central opening in the fan housing or casing, being sucked therein by the revolving fan. The currents of air are equally distributed against the blades and against the inner walls of the casing, and as a consequence serve to retard the free turning of the blast fan in the casing, such currents frequently causing a back pressure against the fan blades, and at all times, incident to the resistance offered thereby add to the labor in a manually operated blast blower. From experience, I have found that by arranging on the outer face of the fan housing a casing of a particular and peculiar shape and construction that the currents of air can be so admitted and directed against the fan blades or wings as to impart an added impetus in the revolution thereof, and consequently materially reduce the manual force employed in turning the fan, and it may therefore be considered the primary object of this invention to provide a blast fan housing or casing with a means for freely admitting air therein in a manner which will assist the revolving of the blast fan therein.

Other objects and advantages will present themselves as the nature of the invention is better understood, reference being had to the drawings which accompany and which form part of this specification.

In the drawings:—

Figure 1 is a front elevation of the head portion or housing of a blast fan illustrating the application of the improvement.

Figure 2 is a sectional view on the line 2—2 of Figure 1.

Figure 3 is a plan view of the improvement looking toward the inner face thereof.

Referring now to the drawings in detail, the numeral 1 designates the head portion or housing of an ordinary blast fan, the same being provided, in the usual manner, with the integral exhaust nozzle portion 2.

55 The housing 1 has its outer face centrally provided with an air admitting opening 3,

and in the housing there is arranged for rotary movement a blast fan which has its blades 4 constructed in the usual manner. The shaft 5 for the blast fan may be provided with the usual worm (not shown) which is engaged by a worm wheel that is actuated by a train of gears operated by a handle in the usual manner. As the gears do not form the subject matter of this invention the same have not been illustrated in the drawings, and have been merely referred to indicate that the fan is turned by hand.

On the outer face of the housing 1 and disposed over the opening 3 there is the body member of my improvement. The body member is hollow and is in the nature of a substantially rectangular casing. The outer wall 6 of the casing is arranged at an outward inclination from the inner wall 7 thereof, the top and bottom walls 8 and 9 respectively, having their edges thus arranged at an angle. The outer wall 6 terminates a distance inwardly from the inner wall, and therefore the top and bottom walls 8 and 9 have their outer ends also cut at an angle. This arrangement provides the casing with a flared air entrance mouth 10. The inner wall 7 does not extend the length of the casing, but terminates at a point away from the center of the opening 3, as clearly disclosed in Figure 2 of the drawings. The top and bottom walls on their inner edges have ears 11 through which pass securing elements in the nature of bolts or screws 12.

The cut away portion of the inner wall provides the casing 13 with an opening 14 that communicates directly with the opening 3 in the housing 1, the elements 12 tightly binding the casing against the outer face of the housing.

On the lower wall 9 of the housing 1 arrange a plurality of upwardly arched air directing members 15 and 16 respectively, the member 15 being of a less length and arranged above the member 16, and the member 16 is in a line with the portion of the wall of the opening 3. The member 16 is also preferably of a greater width than the member 15, and these upwardly arched members are designed to direct the currents of air which enter the mouth 10 of the casing against the fan blade 4 disposed opposite the said director members, and consequently cause such current of air to give an added impetus to the fan in the turning thereof. In order that such currents of air shall be

positively forced into the housing through the opening 3, I arrange upon the top wall 8 of the casing 13 a downwardly arched deflector plate 17 that has its ends terminating 5 approximately in a line with the end of the arched director member 16, the said deflector being also in a line with a portion of the wall of the opening 3.

It is thought that the foregoing description, when taken in connection with the drawings will fully set forth the construction, operation and advantages of the improvement to those skilled in the art to which such inventions relate, and therefore further 10 detailed description is not believed necessary. It is, however, thought well to state that the description and drawings refer to only a satisfactory embodiment of the improvement as it now appears to me and 15 therefore I am entitled to make all such changes therefrom as fall within the scope of what is claimed.

Having described the invention, I claim:—

1. In combination with a hand operated 20 blast blower having an opening communicating with its fan chamber; of a casing having a flared entrance mouth arranged transverse-

ly over and partly covering the opening, spaced upwardly arched members secured to the bottom of the casing for directing air 30 currents against one of the blades of the fan, and a downwardly arched deflector on the top of the casing opposite one of said directors.

2. In combination with a hand operated 35 blast blower having its housing provided with an opening communicating with its fan chamber, of a casing secured transversely on the outer face of the housing over the opening, said casing having its outer wall disposed at an outward angle with respect to its inner wall to provide a flared air entrance mouth, the inner wall being of a less length than the outer wall and only partly closing the opening in the housing, the lower wall of 40 the casing having a plurality of spaced upwardly arched air current directors one of which being arranged in a line with the wall of the opening in the housing, and the upper wall of the casing having a downwardly 45 arched deflector which is also arranged in a line with the opening in the housing.

In testimony whereof I affix my signature.
WILLIAM JEWETT.
